UNITED STATES PATENT OFFICE.

GEORGE HOLT FRASER, OF NEW YORK, N. Y.

CRUSHING-MACHINE.

1,183,808.

Specification of Letters Patent. Patented May 16, 1916.

Application filed December 21, 1905, Serial No. 292,779. Renewed December 14, 1914. Serial No. 877,267.

To all whom it may concern:

Be it known that I, GEORGE HOLT FRASER, a citizen of the United States, residing in the borough of Brooklyn, county 5 of Kings, city and State of New York, have invented certain new and useful Improvements in Crushing-Machines, of which the following is a specification.

This invention relates to machinery for 10 crushing, grinding or pulverizing materials, and aims to provide various improvements therein.

In carrying out this invention, a revolving ring or die having an internal crushing 15 face, and preferably revolving in a substantially vertical plane, is used with one or more internal crushing rolls bearing against the inner face of the die, improved means for carrying the rolls and supporting their 20 bearings are provided, an improved casing is provided for inclosing the crushing parts, and various other improvements are provided which will be hereinafter more fully set forth or shown.

25 In the accompanying drawings which illustrate the preferred form of my invention as applied to a pulverizing mill, Figure 1 is an elevation of the left hand side of the machine partly in vertical section in the 30 planes of the lines 1—1 in Fig. 4, omitting the pulley; Fig. 2 is a front elevation thereof partly in section through the feed hopper in the planes of the lines 2—2 in Figs. 1 and 3, and partly broken out; Fig. 3 is a side 35 elevation of the left hand side of the machine partly in vertical section in the planes of the lines 3—3 in Fig. 2, and partly broken away; and Fig. 4 is a rear elevation partly in vertical mid-section on the line 4—4 in 40 Fig. 3.

I will now describe the preferred adaptation of my invention as applied to a pulverizer of the type shown in the drawings.

Referring to the drawings, A is the main 45 frame or casing, B are the side covers, C is the top bearing frame, D are its bearing caps, E are the lower bearing frames, FR are the bearing caps on their right hand ends, and FL are the bearing caps on their 50 left hand ends, G is the feed hopper.

GR is the right hand feed spout and GL is the left hand feed spout, and GC are the covers giving access to same.

H is the feed deflector, HR is the right 55 hand feed chute and HL is the left hand feed chute.

I are the side hole plates, J are the cheek pieces, K are the end hole plates, L are the spring washers, M are the spring heads, N are the spring seats, O are the bolt locks, P 60 are the dust guards, Q are the bearing links, R is the top rocker, S are the lower rockers, T are the nut locks, U are the thrust collars, V are the driving pulleys, W are the upper oil covers, X are the lower oil covers, Y are 65 the hopper wear plates, Z is the feed gate, ZS is the stop or shut-off gate, ZT is its lever, and ZL is its lock.

The crushing ring is lettered *a*, the rolls *b*, their shafts *c*, the pressure springs *d*, the 70 pressure screws *e*, and the discharge outlet *f*.

The casing preferably incloses and supports the ring and rolls. Each roll has a peripheral crushing face reciprocal to the 75 inner face of the ring. Three rotatable and relatively movable rolls are shown, one at the top and the other two equally disposed within and eccentric of the ring. The inner face of the ring is concave and rests 80 on the convex outer face of the upper roll, which preferably supports it. All of the rolls press outwardly against the inner face of the ring, and this pressure is adjusted by the screws *e* acting against the springs *d* 85 which react against the outer wall of the casing. The pressure of the springs is transmitted by the bearing frames to the shafts of the rolls. The ring and rolls are revolved by driving one of the revolving parts, its 90 motion being transmitted to the others by traction. The pulleys *V* on the top shaft are preferably used to drive these parts. One or more of the rolls are movable radially of the ring, and the ring is preferably 95 movable relatively to the rolls, so that the parts are free to yield to vibration or to adapt themselves to the work between their crushing faces.

Rock enters the inlet *g* in the hopper *G* 100 and flows past the feed gate *Z* on to the hopper plates *Y* in the bifurcated legs of the hopper, by which it is delivered to the spouts at each side of the mill, down which it falls to the chutes, which direct it through the side covers and deliver it onto the deflector *H* inside of the ring and above the feed roll. The deflector deflects the rock on to the inner face of the ring, and it is carried on this face past the rolls, by which it is crushed against the 105 ring. The ring runs freely between the cheek pieces *J*, which are spaced apart from 110

its side faces to prevent large pieces of rock from falling off the ring, and to permit the crushed rock to escape between them and the ring and into the outer casing down which it falls to the outlet. The ring and rolls are driven in such direction that the descending side of the ring will be adjacent to the feed, and at such speed that the centrifugal force will be sufficient to hold the 10 rock on the inner face of the ring until it is ground. The ring and yielding rolls will move to pass uncrushable objects, and preferably each can move axially to a limited extent to adapt themselves to the material being ground.

The casing A is preferably a single annular casting of trough-shaped cross-section, with an opening in one or both sides large enough to pass the ring into its grinding chamber, and is provided with suitable end holes communicating with this chamber and with a base *h* through which the outlet *f* passes. The side openings of the annular casing are preferably oval or of greater 25 height than width, so that the strength of the casing near its horizontal center is increased. This does not prevent entrance or removal of the ring, however, as the ring can be rotated on a vertical axis until it 30 passes the side edges of the opening, and then moved or rolled out of the casing. Opposite each roll the casing has a bearing portion for the corresponding bearing frame or its spring, and intermediate of the rolls 35 it has provisions for supporting the roll bearings and their frames from points exterior of the ring. The cross-section of the casing is shown as U-shaped, and it is provided with internal flanges *s* opposite the 40 crushing rolls, and is protected from wear by wear plates *i* carried in the pockets formed by these flanges. These flanges reinforce the casing and are interrupted opposite the hand holes to give free passage at such 45 points. The casing is widened where the flanges are interrupted to give additional strength, and exteriorly it is provided with a reinforcing rib *t*, and with pivotal provisions *j* for the guiding links *Q*, and *k* 50 for the top rocker *R* and *l* for the lower rockers *S*. The inner edge of the casing is formed with notches *m* for receiving ears *n* on the cheek pieces to insure proper positioning thereof, see Fig. 3.

55 The side openings in the casing are closed by the covers *B*, which are each a single piece formed with slots for the shafts, and hand holes for access and holes for the feed chutes. The covers *B* are machined on their 60 inner faces to fit against the machined strips on the outer faces of the casing and on their outer faces around the slots and holes, and each cover is bolted against one side of the casing so that the roll shafts project 65 through the slots.

The cheek pieces *J* are preferably rings having flat faces opposite the sides of the revolving ring when the latter is flat-sided, or tapering faces when the sides of the ring are tapered, and each cheek piece is fastened to the adjacent cover with a machine-fitted joint, and has an ear or ears *n* for fitting in the corresponding notch *m* in the casing. Each cheek piece has an inner recess *o* for clearing the feed chute, the ears 70 and recesses being shown as duplicated, so that a cheek piece can be used on either side of the mill. The lower part of each cheek piece is recessed at *p* (Fig. 4) to permit ground material to escape to the outlet. 75 The cheek pieces are fastened on the covers, and then the two are applied to the casing by slipping the covers over the ends of the shafts.

The dust guards *P* are bored to fit the 80 shafts, and faced to make a tight joint against the cover, and are shaped to cover the shaft slot in all movements of the shaft. They are supported by the bearing frame by projecting lugs *u* which fit slidingly into 90 the rabbeted lugs *v* on the frame, and are held therein by the adjacent face of the lugs *w* bearing cap, which engage lugs *x* on the guards *P*. The coiled spring reacting against the bearing and guard and held 95 between these lugs, keeps the guard against the cover as shown, so that the guard does not participate in axial movements of the frame, but does participate in all radial movements of the bearing.

100 The hopper has a poke-hole *y* behind its inlet for cleaning out. The feed gate has a notched end to insure a central flow of feed to the spouts, and is adjusted in its slide-way by a screw which is separably connected to it as shown. The shut-off gate has a sliding support in its movements toward and from the closed position in its slideway, being carried on its inner end by beveled tracks, and on its outer end by the swinging 105 handle *ZT*, which is pivoted above it, and is locked in its closed and open positions by the gravity lock *ZL* which hooks against the hopper or casing. This swinging facilitates opening and closing movements of the gate, 110 and reduces friction.

115 As shown in Figs. 2 and 3, the upper wear plates *Y* lie in the hopper legs and protect their lower sides. The hopper overhangs the casing and supports the spouts which are clamped to its under face. The lower end of each spout fits over and closes the corresponding hand hole on the adjacent cover. Each cover *B* is formed with an integral flange *z* for supporting the deflector *H* (Fig. 120 125 2) which rests with its ends on these flanges between the spouts, and has a central projection *a* preventing material from jumping across from one spout to the other, and causing material coming down either spout to 130

flow on to the ring near the center of its face. The chutes rest with their inner ends on the deflector and abut against shoulders b' thereon, while their outer ends project 5 loosely into the spouts and rest therein, thus protecting these from wear. The deflector may be reversed when one side is worn. The chutes may be renewed through the spouts, and the hopper plates may be removed through the hand hole in the hopper 10 when it is necessary to substitute others.

The bearings are shown as swinging non-rotative carriers or members movable toward and from each other and preferably 15 pivotally connected to and positioned or supported and guided by links Q which are movable swinging members preferably pivotally connected to the ears j at their outer ends, and to the respective bearing 20 frames at their inner ends. The bearings at the opposite ends of the shafts are preferably rigidly united by a U-shaped frame, shown as a single casting extending around the outside of the casing, and supported near 25 its outer end movably from the casing, and having a spring pocket or provision for the pressure spring. The top frame C is preferably positioned or guided by the rocker R, which is a movable or swinging member 30 preferably pivoted to the ear k , and guides the frame and prevents its oscillation, as it is pressed upwardly by suitable means as its spring d . This frame is formed with oil and grease wells above each bearing, which are 35 closed by the gravity doors W as shown. Its bearing caps D are planed bearing caps rabbed into the frame to insure alinement, the frame and caps having lugs and flanges at their inner faces opposite the dust guards 40 and their springs, for supporting them. At their outer ends this frame and its caps project out close to the pulleys, and have planed ends against which antifriction washers, which are between the hubs of the pulleys 45 and the frame, limit endwise movement of the shaft in the bearings. The hubs of the pulleys are constructed thus as thrust hubs, and these hubs and the ends of the shaft are drilled through and locked by a cross bolt 50 to prevent shifting of the pulleys, see Fig. 4.

The lower frames E are non-rotative swinging carriers or members movable toward and from each other and pivotally positioned or supported near their outer ends 55 by the rockers S, which are shown as divergently inclined thrust or compression members. Their caps FR and FL are provided with integral grease and oil wells which are closed by the covers X as shown. The links 60 Q for lower frames E are shown as reversely inclined tension members. These frames and caps are constructed like the upper ones on their inner ends, but on their outer ends they are shorter and receive the thrust of 65 the thrust collars U, which are fixed to the

lower shafts by through bolts, as above described, and are provided with antifriction washers between their inner faces and the bearings. These washers are countersunk on their outer faces, so that they slightly overhang the beveled inner edge of the collars. The nut locks T are pivoted to fall by 70 gravity or under light spring pressure over the nuts, and the heads of the bolts are prevented from turning by lugs on the various 75 frames and caps as shown.

The swinging, guiding, and supporting of the top frame, is done from one side, and that of the lower frames is done from opposite sides, of its bearing, and the relation of 80 the supporting links and rockers is proportioned to suit the requirements of work. As shown, the angularity of the lower rockers is suitable to utilizing part of the weight of the frame for drawing the roll outwardly 85 against the inner face of the ring, thus increasing the effectiveness of this weight as a crushing force whether or not it is used in conjunction with the spring pressure. This swinging guidance of the bearing 90 frames involves some oscillation of the spring pocket, but the movement of the rolls is too slight to make this material. To provide for such oscillation, the spring seat N is formed with a semi-spherical concavity, 95 and a corresponding protuberance on the casing is provided, as shown.

The spring is shown as secured in a cage, so that its motion is limited to approximately two inches expansion or contraction, 100 thus correspondingly limiting the inward and outward movements of the rolls. The square head of the spring bolt fits in a squared socket in the spring head M, and the nut of this bolt can be turned in the 105 round socket in the spring seat N until it strikes a shoulder on the bolt, which will be made to suit the initial compression desired. Then the nut can be locked, and the length of the bolt will limit the outward expansion 110 of the spring. The inward compression of the spring can be limited by the abutting of the spring head and spring seat. The spring washer fits loosely in the spring head and receives the end of the pressure screw. To 115 prevent the pressure screw from jarring out of adjustment, the automatic lock O is provided, which has a socket fitting over the head of the screw, and legs fitting slidingly in holes passing through the end of the 120 spring pocket. For the upper frame the lock O is pressed outwardly by a light spring. For the lower frames it may be spring-operated, or it may operate by gravity, as shown. To adjust a pressure screw, 125 the lock O is moved in and held until the screw has been turned, and is then released, whereupon it engages the head of the screw and locks it. In case the top screw is removed, undue descent of the top frame is 130

prevented by the spring bolt *q*, which is of such length that the spring washer will strike it before the top shaft has fallen too low. The holes for the lock *O* in the end 5 of the spring pocket, permit dirt to sift out of the lower pockets if it accumulates therein.

The bearing frames are provided with stops or rollers *r*, removably connected to 10 their bearing ends, which work against the side covers with a slight clearance and permit the bearings to oscillate slightly with the end thrust of the shafts, but arrest this oscillation at the predetermined limit. This 15 enables the bearings to be practically stationary relatively to the shafts, while permitting a limited end play for the rolls. The rolls are held on the shafts by shoulders and collars and bolts in any ordinary or suitable way. In operation, the bearings will 20 swing in and out slightly, and will oscillate slightly to adapt themselves to the exigencies of the work and avoid rigidity. If wearing parts are to be renewed, the bearing caps 25 will be unbolted from their frames, and the latter will be swung outwardly until they are out of the way of the side covers. Then one or both side covers will be removed, and the rolls and shafts withdrawn. The ring 30 will be turned edgewise until it will pass out through the side of the casing, whereupon it will be rolled out and another can be replaced. The cheek pieces will be removed if necessary and new ones attached 35 to the covers. To reassemble the mill, the shafts and rolls will be replaced within the ring after the latter has been moved into the casing, the covers will be applied, the bearing frames swung back into position, 40 the caps replaced, the parts connected up, and operation may be resumed. In moving the bearing frames outwardly, it is desirable to disconnect the links and oscillate the frames on the rockers. The gates *Z* are bevelled on their edges which slide on the tracks and are graduated on their sides to indicate 45 their position, and their tracks do not extend to the rear end of the hopper.

It is obvious that the machine described 50 may be built with extreme simplicity and compactness in all its parts and with sufficient elasticity to meet all possible requirements, and that this, to a large extent, is due to the swinging support for the non-rotative members carrying the rolls. To 55 accomplish this swinging support various forms of specific construction may be employed, the form shown and described being regarded merely a specific example to 60 which, however, the scope of this invention is not restricted. It will also be understood that the constructions and arrangements shown and described are given as examples illustrating the preferred form of this invention, but that the invention may be

availed of in whole or in part in any modified form which circumstances or the judgment of those skilled in the art may dictate, without departing from the spirit of this invention.

70

What I claim is:—

1. In a crushing machine having a revolving ring and a crushing roll acting against its inner face, the combination with a casing inclosing the ring and roll and having an opening large enough to pass said ring, of movable bearings for the roll shaft at opposite sides of the casing, a rigid frame uniting said bearings and extending around the exterior of the casing, and a swinging 80 guide for said frame.

2. In a crushing machine having a revolving ring and a crushing roll acting against its inner face, the combination with a casing inclosing the ring and roll and having an opening large enough to pass said ring, of movable bearings for the roll shaft at opposite sides of the casing, a rigid frame uniting said bearings and extending around the exterior of the casing, means 85 movably supporting said frame near its bearings, and a guide for the outer end of said frame.

3. In a crushing machine having a revolving ring and a crushing roll acting against its inner face, the combination with a casing inclosing the ring and roll and having an opening large enough to pass said ring, of movable bearings for the roll shaft at opposite sides of the casing, a rigid frame uniting said bearings and extending 95 around the exterior of the casing, and a swinging guide for said frame near its bearings, and a support for the outer part of said frame.

4. In a crushing machine having a revolving ring and a crushing roll acting against its inner face, the combination with a casing inclosing the ring and roll and having an opening large enough to pass said ring, of movable bearings for the roll shaft at opposite sides of the casing, a rigid frame uniting said bearings and extending 100 around the exterior of the casing, means movably guiding said frame near its bearings, and a swinging guide for the outer 105 part of said frame.

5. In combination, an annular crushing die revolving in a vertical plane and having an internal crushing face, a movable and rotatable crushing roll within, eccentric to 110 and disposed near the upper part of, said die and having a crushing face reciprocal to that of the latter, means for revolving one of said parts, a non-rotative movable pivotally mounted member carrying said 115 roll, and means pressing said roll upwardly toward said die to resist a crushing pressure from the inner face of the latter.

6. A crushing machine comprising a revolving ring and a crushing roll therein, in 120

125

130

combination with a casing inclosing said parts consisting of a single annular casting having a chamber larger than said ring and an aperture large enough to pass said ring, 5 having guiding provisions for the bearings of said roll at opposite sides of said roll and beyond the periphery of said ring, and a frame extending across the exterior of said casing for connecting said bearings together.

7. A casing for crushing machinery having a side opening for receiving a cheek piece, in combination with a cheek piece smaller than, entering, and inclosed within, 15 said opening, said piece and casing having reciprocal recesses and projections for positioning said parts, and means supporting said piece from the outside of said casing.

8. For crushing machinery, a bearing 20 frame having bearing portions at its extremities, guiding provisions adjacent thereto, pivotal provisions, a U-shaped body between said bearing portions, and a spring pocket in said body having an aperture 25 through its wall for receiving a lock.

9. A bearing frame for crushing machinery having bearing portions near its extremities, stop provision adjacent thereto, a U-shaped body connecting said portions, 30 and pivotal provisions on said body remote from said portions, said frame movable both axially and radially of said bearing portions, a revolving crushing member carried by said frame, and means movably supporting said frame.

35 10. In combination, an annular crushing die revolving in a vertical plane and having an internal crushing face, three movable rotatable crushing rolls within and eccentric 40 to said die, said rolls movable toward and from one another and each having a crushing face reciprocal to that of said die, means for revolving one of said parts, non-rotative movable pivotally mounted carriers for said 45 rolls respectively, and means pressing said rolls apart to generate a crushing pressure toward the inner face of said die.

11. In combination, an annular crushing 50 die revolving in a vertical plane and having an internal crushing face, a plurality of movable and rotatable crushing rolls within and eccentric to said die and each having a crushing face reciprocal to that of the latter, means for revolving one of said parts, 55 non-rotative and swinging carriers for said rolls respectively, pivotally mounted above said rolls and means holding said rolls toward said die to resist a crushing pressure from the inner face of the latter.

60 12. A rocker for crushing machinery having an open-sided semi-cylindrical portion for embracing and making a pivotal connection with a pivotal provision near one of its extremities, and having pivotal provisions 65 near its other extremity in combination with

a movable bearing member connected to last mentioned provisions.

13. In combination, an annular crushing die revolving in a vertical plane and having an internal crushing face, a plurality of movable and rotatable crushing rolls within and eccentric to said die each having a crushing face reciprocal to that of the latter, means for revolving one of said parts, and non-rotative relatively movable swinging carriers 70 for said rolls respectively, each pivotally mounted above and outwardly of its roll, whereby each carrier tends to swing its roll outwardly.

14. In combination, an annular crushing die revolving in a vertical plane and having an internal crushing face, a plurality of movable and rotatable crushing rolls within and eccentric to said die, disposed on approximately the same horizontal plane, and each having a crushing face reciprocal to that of the die, means for revolving one of said parts, non-rotative movable carriers 80 for said rolls respectively, and outwardly diverging tension members pivotally mounted 85 above and outwardly of said rolls and carrying said carriers.

90 15. In combination, an annular crushing die revolving in a vertical plane and having an internal crushing face, a movable and rotatable crushing roll within and eccentric to said die and having a crushing face reciprocal to that of the latter, means for revolving one of said parts, a non-rotative and movable carrier for said roll, and an inclined 95 thrust member beneath and acting against said carrier to force said roll outwardly, and pivotally mounted inwardly of and below its point of engagement with said carrier.

100 16. In combination, an annular revolving crushing die having an internal crushing face, a plurality of movable and rotatable crushing rolls within and eccentric to said die, each having a crushing face reciprocal to that of the latter, means for revolving one 110 of said parts, non-rotative and relatively movable carriers for said rolls respectively, and reversely inclined pivotally mounted diverging thrust members acting against said carriers respectively to force said rolls apart. 115

120 17. A revolving crushing ring and a crushing roll therein, in combination with a casing inclosing said parts, the top bearing frame herein set forth for said roll, and the rocker herein set forth for said frame consisting of a member having spaced pivotal provisions at its ends for connecting said casing and frame movably together and having recesses between said provisions for receiving said casing and frame respectively. 125

18. In combination, an annular crushing die revolving in an approximately vertical plane and having an internal crushing face, a movable and rotatable crushing roll within, eccentric to, and disposed near the 130

upper part of, said die, and having a peripheral crushing face reciprocal to the internal face of the latter, means for revolving one of said parts, a non-rotative movable member on which said roll is rotatably mounted, means pressing said roll upwardly toward said die to resist a crushing pressure from the inner face of the latter, a frame or casing for said parts, and an additional member 10 removably connected to said frame or casing and on which said non-rotative member is movably mounted.

19. In combination, an annular crushing die revolving in an approximately vertical plane and having an internal crushing face, a movable and rotatable crushing roll within, eccentric to, and disposed near the upper part of, said die, and having a peripheral crushing face reciprocal to the internal face 20 of the latter, means for revolving one of said parts, non-rotative means on which said roll is rotatably mounted, means holding said roll upwardly toward the inner face of said die to resist a crushing pressure from the latter, a frame or casing for said parts, and an additional member pivotally connected to 25 said frame or casing and on which said non-rotative member is mounted.

20. In combination, an annular crushing die revolving in an approximately vertical plane and having an internal crushing face, a movable and rotatable crushing roll within, eccentric to, and disposed near the upper part of, said die, and having a peripheral 30 crushing face reciprocal to the inner face of the latter, means for revolving one of said parts, non-rotative swinging means on which said roll is rotatably mounted, means holding said roll upwardly and toward the inner face of said die to resist a crushing pressure therefrom, a frame or casing for said parts, and an additional member pivotally connected to 35 said frame or casing and on which said swinging member is pivotally mounted.

40 21. In combination, an annular crushing die revolving in an approximately vertical plane and having an integral crushing face, a plurality of rotatable crushing rolls movable toward and from each other within, eccentric to, and each having a peripheral 45 crushing face reciprocal to the internal face of, said die, means for revolving one of said parts, non-rotative movable members on which said rolls are rotatably mounted respectively, means acting to press said rolls away from one another to resist a crushing pressure from the inner face of said die, a frame or casing for said parts, and means for positioning said non-rotative members 50 pivotally connected to said frame or casing and on which said non-rotative members are movably mounted.

55 22. In combination, an annular crushing die revolving in an approximately vertical plane and having an internal crushing rolls 60

three or more rotatable crushing rolls within and eccentric of said die and each having a peripheral crushing face reciprocal to the inner face of the latter, means for revolving one of said parts, non-rotative carriers 70 on which said rolls are rotatably mounted respectively, means for holding said rolls away from one another to resist a crushing pressure from the inner face of said die, a frame or casing for said parts, and means movably mounted on said frame or casing and on which said non-rotative members are mounted.

23. In combination, an annular crushing die revolving in an approximately vertical plane and having an internal crushing face, two or more rotatable crushing rolls movable toward and from each other within and eccentric of said die and each having a peripheral crushing face reciprocal to the internal face of the latter, means for revolving one of said parts, swinging means on which said rolls are rotatably mounted respectively, a frame or casing for said parts, means pressing said rolls away from one another to resist a crushing pressure from the inner face of said die, and pivoted means connected to said casing and on which said swinging means are pivotally mounted.

24. In combination, an annular crushing die revolving in an approximately vertical plane and having an internal crushing face, two or more rotatable crushing rolls movable toward and from each other and as a group, within and eccentric of said die, and each having a peripheral crushing face reciprocal to the inner face of the latter, means for revolving one of said parts, non-rotative movable means on which said rolls are rotatably mounted respectively, a frame or 95 casing for said parts, means for holding said rolls outwardly away from one another to resist a crushing pressure from the inner face of said die, and supporting means on which said non-rotative means are movably mounted on said frame or casing.

25. In combination, an annular crushing die revolving in an approximately vertical plane and having an internal crushing face, two or more rotatable crushing rolls movable toward and from each other and as a group, within and eccentric of said die, and each having a peripheral crushing face reciprocal to the inner face of the latter, means for revolving one of said parts, non-rotative movable means on which said rolls are rotatably mounted respectively, a frame or casing for said parts, means for holding said rolls outwardly away from one another to resist a crushing pressure from the inner face of 115 said die, and supporting means on which said non-rotative means are movably mounted pivotally connected to said frame or casing.

26. In combination, an annular crushing 120

die revolving in an approximately vertical plane and having an internal crushing face, two or more rotatable crushing rolls within and eccentric of said die and each having a peripheral crushing face reciprocal to the inner face of the latter, means for revolving one of said parts, non-rotative movable carriers on which said rolls are rotatably mounted respectively, means for press-
10 ing said carriers outwardly away from one another to generate a crushing pressure toward the inner face of said die, a frame or casing for said parts, and hinged means on which said carriers are movably mounted,
15 connecting the latter to said frame or casing.

27. In combination, an annular crushing die revolving in an approximately vertical plane and having an internal crushing face, three rotatable crushing rolls movable to-
20 ward and from each other and as a group, within and eccentric of said die and each having a peripheral crushing face reciprocal to the inner face of the latter, means for revolving one of said parts, non-rotative mov-
25 able carriers on which said rolls are rotatably mounted respectively, means acting on said carriers to hold said rolls outwardly away from one another to resist a crushing pressure from the inner face of said die, a
30 frame or casing for said parts, and hinged means on which said non-rotative carriers are movably mounted.

28. In combination, an annular crushing die revolving in an approximately vertical plane and having an internal crushing face, a movable and rotatable crushing roll within, eccentric of, and disposed near the upper part of, said die, and having a peripheral crushing face reciprocal to the inner
35 face of the latter, means for revolving one of said parts, a casing for said parts having an opening at the side of said roll, an upwardly movable non-rotative carrier on which said roll is rotatably mounted, means
40 acting on said carrier to press said roll upwardly to resist a crushing pressure from the inner face of said die, and an upwardly movable plate covering said opening and slidably mounted on said carrier.

50 29. In combination, an annular crushing die revolving in an approximately vertical plane and having an internal crushing face, a movable and rotatable crushing roll within and eccentric to said die and having a peripheral crushing face reciprocal to the inner face thereof, means for revolving one of said parts, a casing for said parts having an opening at the side of said roll, a non-rotative carrier at the side of said casing

opposite said opening, movable approxi- 60 mately radially of said die, on which said roll is rotatably mounted, a spring acting on said carrier to press said roll toward the inner face of said ring to resist a crushing pressure therefrom, and a spring-pressed 65 plate closing said opening and movable radially of said die.

30. In combination, an annular crushing die revolving in an approximately vertical plane and having an internal crushing face, 70 a rotatable crushing roll within, eccentric to and movable approximately radially of, said die and having a crushing face reciprocal to the inner face of the latter, means for revolving one of said parts, a casing for said parts 75 comprising a removable side having an opening opposite said roll, a non-rotative bearing or carrier at the side of said casing opposite said opening movable approximately radially of said die and on which said roll 80 is rotatably mounted, means acting on said bearing or carrier to press said roll outwardly toward the inner face of said die to resist a crushing pressure therefrom, means within said die for directing material to be 85 crushed onto the inner face thereof in advance of said roll, and means carried by said removable side communicating with said directing means for affording a conduit or 90 passage for material from without said cas- ing to within said ring.

31. In combination, an annular crushing die revolving in an approximately vertical plane and having an internal crushing face, two or more rotatable crushing rolls mov- 95 able toward and from each other, within and eccentric to said die and each having a peripheral crushing face reciprocal to the inner face thereof, means for revolving one of said parts, a casing for said parts comprising a removable side, non-rotative carriers on which said rolls are rotatably mounted respectively, a spring or springs for pressing said rolls outwardly away from one another to resist a crushing pressure 100 from the inner face of said die, and means carried on said removable side comprising a conduit or passage communicating with the interior of said die intermediate of said rolls for directing material to be crushed onto the 105 inner face of said die.

In witness whereof, I have hereunto signed my name in the presence of two sub-
scribing witnesses.

GEORGE HOLT FRASER.

Witnesses:

THOMAS F. WALLACE,
FRED WHITE.
